UNITED STATES PATENT OFFICE.

GEORGE M. PETTENGILL, OF HAVERHILL, MASSACHUSETTS, ASSIGNOR, BY MESNE ASSIGNMENTS, TO HAMEL SHOE MACHINERY COMPANY, OF LYNN, MASSACHUSETTS, A CORPORATION OF MASSACHUSETTS.

HEELING-MACHINE.

1,170,321.

Specification of Letters Patent.

Patented Feb. 1, 1916.

Application filed June 11, 1914. Serial No. 844,546.

To all whom it may concern:

Be it known that I, GEORGE M. PETTENGILL, a citizen of the United States, residing at Haverhill, in the county of Essex and State of Massachusetts, have invented an Improvement in Heeling-Machines, of which the following is a specification.

This invention relates to certain improvements in heeling machines, and more particularly to heeling machines of the type shown and described in my Patent #1,119,763, dated Dec. 1, 1914, in which one heel is pricked by awls on an awl-block, which is connected to the cross-head, while the top lift is being spanked onto another heel which has just been attached to the shoe, and the awl-block is sustained, inoperative, independently of the cross-head, while the attaching or nail-driving operation is being performed. In the machine disclosed in my said prior patent, frictional devices were employed for sustaining the awl-block during the nail driving operation, and, with this frictional engaging means, it has been found that, under some conditions, the jar of the machine which occurs at the time the down-stroke is finished, causes the awl-block to become disengaged from its support, so that it falls until the awls strike the nail-plate slide, which, at that time, is directly therebeneath, thereby causing the awls to become dulled or broken.

The object of the present invention is to provide means for positively supporting the awl-block during the nail-driving operation, so that the awl-block can not possibly become disconnected from the parts which support it, and the awls are prevented from being struck on the top surface of the nail-plate. I accomplish this object by providing a locking means which will be caused to move into engagement with the awl block whenever the nail-plate is moved forward beyond the pricking position and which will be caused to remain in this position until the nail-plate is again retracted.

For a more complete understanding of my invention reference is made to the accompanying drawings, in which,

Figure 1 is a front elevation of the cross-head of the machine illustrating certain parts thereof. Fig. 2 is a plan view thereof. Fig. 3 is a cross-sectional view taken on the

line 3—3 of Fig. 1. Fig. 4 is a detail view 55 of a portion of the operating mechanism.

Inasmuch as a complete description of the entire machine may be found in said prior application, only those parts have been shown which necessarily coöperate 60 with the particular invention to which this application relates.

As shown in the drawing, the cross-head 6 has the turret 7 mounted in the head in the usual manner. The nail-plate 17 is 65 mounted in guideways in the nail-plate-holder 14, and is adapted to be moved to nailing position over the jack, or into pricking position over the heel-holder, disposed directly in the rear thereof, (neither being 70 shown). The awl-carrier 28 is slidably mounted between the holder 14 and the cross-head and is adapted to be locked to the latter by the locking shaft 51, which is moved into and out of locking position 75 upon rotation of the turret.

In said prior patent I have illustrated a safety mechanism for the turret which prevents the nail-plate from being moved into nailing position over the jack when the turret 80 is in spanking position, and also prevents the turret from being moved from nailing position into spanking position when the slide is in nailing position over the jack. This mechanism is illustrated in the 85 present drawings, and comprises a vertically disposed rod 84 mounted on the holder 14 at its lower end, and having an arm 85 secured thereto, which is arranged to be engaged and swung aside by the nail-plate 90 slide 17, when the latter is moved forward beyond the pricking position and a finger 86 is splined on said shaft and is arranged to engage a notch in the turret to lock the same. In the particular embodiment of my 95 invention shown, I employ this safety mechanism in performing the additional function of locking the awl carrier in raised position during the driving operation of the cross-head. To accomplish this result the 100 rod 84 is extended upward above the upper end of the cross-head, and a finger 110 is secured on said extended upper end. The awl carrier 28 is provided with an extension 28' which has a lateral projection 28'' 105 at its upper end, said finger 110 and said projection 28'' being so arranged that, in certain positions of rotation of said rod 84,

said finger will be held directly beneath said projection and will sustain the awl-carrier in its raised position. The relative position of said finger 110 and said arm 85 is such that, when the arm 85 is swung forward by the nail-plate slide, as the latter is moved forward beyond the front end of holder 14, so that the finger 86 locks the turret, the finger 110 will be swung beneath the projection 28", so that it will lock the awl carrier in raised position, as shown in Fig. 1.

To describe the operation more completely, when the cross-head moves upwardly, after the pricking operation is finished, the pin 100 therein engages the awl-carrier 28 and lifts it to its highest position, as shown in Fig. 3. The nail-plate slide is then pushed forward and swings the finger 110 beneath the projection 28", as before described. The shaft 84 will remain in this position, holding the finger 110 beneath said projection while the nailing-operation is performed, so that, when the cross head moves down to perform the nailing operation, the awl carrier will be sustained in its raised position during the entire nailing operation, and will not be permitted to fall so that the awls will strike the nail-plate slide. When the nailing operation has been finished and the nail-plate is drawn back to pricking position, the spring 88 will rotate the shaft 84, and will move the finger 110 from beneath the projection 28", so that the awl carrier will no longer be locked in raised position, and, when the turret is rotated into spanking position, the locking bolt 51 will be moved into engagement with the carrier 28, so that the pricking operation will be performed on the next movement of the cross-head.

I claim:

1. In a heeling machine of the character described, a vertically movable head, a nail plate, movable beneath said head between driving and pricking positions, a vertically movable awl carrier disposed adjacent said head, means to connect and disconnect said head and said carrier, a locking device supported independently of said head and movable between positions to lock said awl carrier in raised position and to unlock it to permit it to move downwardly with the head, means, actuated on movement of the nail plate to driving position, to move said locking device into locking position, and means to return said locking device to unlocking position when the nail plate is moved into pricking position.
2. In a heeling machine of the character described, a vertically movable head, a nail plate, movable beneath said head between driving and pricking positions, a vertically movable awl carrier disposed adjacent said head, means to connect and disconnect said

head and said carrier, a locking device supported independently of said head and movable between positions to lock said awl carrier in raised position and to unlock it to permit it to move downwardly with the head, 70 an actuator for said locking device arranged to be engaged by the nail-plate, as it is moved from pricking to driving position, to move said locking device to locking position, and means to return said locking device to unlocking position when the nail-plate is moved to pricking position.

3. In a heeling machine of the character described, a vertically movable head, a nail-plate movable beneath said head between 80 pricking and driving positions; a turret mounted on the head movable to driving and top-lift spanking positions, a vertical movable awl-carrier disposed adjacent said head, means to connect and disconnect said head and said carrier, a locking device, constructed and arranged simultaneously to lock said turret in spanking position and said carrier in raised position and movable between positions to lock and unlock the 90 same, means, actuated on movement of the nail-plate to driving position, to move said locking device to locking position and means to return said device to unlocked position when said nail-plate is moved to pricking 95 position.

4. In a heeling machine of the character described, a vertically movable head, a nail-plate movable beneath said head between 100 driving and pricking positions, a vertically movable awl-carrier disposed adjacent said head, means to connect and disconnect said head and said carrier, a locking device supported independently of the head, inter-engaging projections on said locking device 105 and carrier arranged to support said carrier in raised position when the head is lowered for the driving operation, and means to move one of said projections into engagement with the other when the nail-plate is moved from pricking to driving 110 position, and to move it out of engagement therewith when the nail plate is returned to pricking position.

5. In a heeling machine of the character 115 described, a head vertically movable to perform the heel-pricking and nail-driving operations, successively, a vertically movable awl carrier disposed adjacent said head, means to connect and disconnect said head and said carrier, a locking device supported independently of said head and movable to support said carrier in its raised position independently of the head and to release it to permit it to be lowered with the head, 125 and actuating means to move said locking device alternately between its supporting and releasing positions to correspond to the successive nail-driving and heel-pricking movements, respectively, of said head.

6. In a heelng machine having a head vertically movable to perform heel-pricking and nail-driving operations successively, a vertically movable awl carrier disposed adjacent said head, means to connect and disconnect said head and said carrier, a shaft supported independently of said head and having an arm thereon arranged to be moved into engagement with said carrier, 10 when said carrier is in raised position, to support the same independently of the head, and to release the same to permit it to be lowered with the head, and means to move

said shaft alternately between its supporting and releasing positions to correspond 15 to the successive nail-driving and heel-pricking movements, respectively, of the head.

In testimony whereof, I have signed my name to this specification, in the presence 20 of two subscribing witnesses.

GEORGE M. PETTENGILL.
